No. 793,205.

PATENTED JUNE 27, 1905.

H. K. J. MANGER.
RAILWAY TIE.
APPLICATION FILED MAR. 22, 1905.

UNITED STATES PATENT OFFICE.

HENRY K. J. MANGER, OF ST. LOUIS, MISSOURI.

RAILWAY-TIE.

SPECIFICATION forming part of Letters Patent No. 793,205, dated June 27, 1905.

Application filed March 22, 1905. Serial No. 251,477.

To all whom it may concern:

Be it known that I, HENRY K. J. MANGER, a citizen of the United States, residing at St. Louis, State of Missouri, have invented certain new and useful Improvements in Railway-Ties, of which the following is a full, clear, and exact description, reference being had to the accompanying drawings, forming a part hereof.

10 My invention has relation to improvements in metallic railway-ties; and it consists in the novel construction of tie more fully set forth in the specification and pointed out in the claims.

15 In the drawings, Figure 1 is a vertical longitudinal section on the broken line 1 1 of Fig. 2. Fig. 2 is a top plan of a section of the completed track. Fig. 3 is a bottom plan view of the tie. Fig. 4 is a plan of the original 20 blank from which the body of the tie is formed. Fig. 5 is a vertical transverse section on line 5 5 of Fig. 1. Fig. 6 is a detail plan of the rail-supporting plate and spacing-block for the rails. Fig. 7 is a side elevation 25 of the rail-supporting plate and packing supporting the same. Fig. 8 is a side elevational detail with parts broken away, showing the abutting ends of two rails and spacing-block between them. Fig. 9 is a perspective of the 30 spacing-block. Fig. 10 is a perspective of the rail-clamp, and Fig. 11 is a plan of the original blank from which is formed the boxing disposed at each end of the tie.

The object of my invention is to construct 35 a metallic tie which shall be simple, cheap to construct, durable, one which can be securely bound to the road-bed, thereby preventing creeping either longitudinally or laterally, one which is elastic, and one possessing further 40 and other advantages better apparent from a detailed description of the invention, which is as follows:

45 Referring to the drawings, 1 represents the tie formed from a single sheet of metal, Fig. 4, bent along the dotted lines *a a b b* and forming the resulting depending marginal flanges 2 3, as shown in Fig. 1. The adjacent ends of the treads of the contiguous rails *R* are formed into tongues 4 and grooves 5, respectively, the tongue projecting beyond the

web and flange of the rail, a suitable spacing-block 6 being interposed between the rails, the flange and web being sufficiently cut away or recessed to allow the insertion of the head of said block, Fig. 8. This block completes the continuity between the rails and serves as a bond which insures firmness for the several rails of the track. The block is provided with a stem 7, which passes through an opening 8, formed in the tie. The tongue and groove insures a continuity for the rail-tread, thus preventing the thumping of the trucks of the cars as they pass over the joints between the rails.

The adjacent ends of the rails are supported 65 on plates 9, each plate having formed therefrom a rounded tongue 10, which enters a corresponding groove formed along the bottom of the rail, thus securely locking the rail to the plate and the plate to the rail. The plate 70 rests on a cushion of fiber or equivalent yielding layer 11, having an inner flange 12 embracing the edge of the layer 11 on one side and an outer flange 12' embracing the layer 11 and the end of the tie 1, Fig. 1. Both the 75 plate 9 and cushion 11 have alining openings for the free passage therethrough of the stem 7 of the spacing-block 6. The rails are secured to the tie by clamps 13, each clamp overlapping the rail-flange and having an inner locking-arm 14 inserted through openings 80 15 of the tie and plate 9, respectively. Once in position, the clamp is secured by a bolt 16, the nut 17 of which has passed, preferably, thereover a grease-cup 18, containing grease 85 to prevent rusting of the nut and held frictionally to said nut, as shown in Fig. 1.

Beneath each tie under the rails is secured an open box *B*, formed, preferably, of a single sheet or blank 19, as shown in Fig. 11, 90 and folded along the dotted lines *c c d d e e f f*, and slits *g*, the body of the blank forming the base of the box secured directly to the tie by the same bolts 16 which secure the clamps 13. The sections 20 20 of the blank 95 and the wings 21 21 jointly form a depending mouth for the completed box, which mouth is embedded into the road-bed, and thus prevents the tie from shifting either longitudinally or laterally. The sections 20 20 are 100

provided with openings O, which in the completed box register with one another for the reception of suitable pipes or conduits P, primarily intended for the housing of telegraph-wires, telephone-wires, and the like, or it may even be used to conduct water to the water-tanks of the road.

From the foregoing it is apparent that the advantages enumerated are inherent in the 10 construction as shown.

I do not wish, of course, to be limited to the specific details here shown and described, as they may in a measure be departed from without in any wise affecting the nature or 15 spirit of my invention.

Having described my invention, what I claim is—

1. A railway-tie comprising a metal body portion, a rail-supporting plate have a tongue 20 engaging a basal groove of the rail disposed at each end of the tie, a cushioning layer interposed between the plate and tie and means for preventing shifting of the tie on the road-bed, substantially as set forth.

2. A railway-tie comprising a sheet-metal body portion having marginal depending flanges, a rail-supporting plate at each end of the tie, a cushioning layer interposed between the plate and tie, a tongue formed in the plate 30 and engaging a groove at the bottom of the rail, and means for clamping the rail to the tie, substantially as set forth.

3. A railway-tie comprising a sheet-metal body portion, a rail-supporting plate at each 35 end of the tie, a spacing-block resting on the plate between the adjacent ends of two contiguous rails, and a stem formed on the block and passing through the plate and tie-body, substantially as set forth.

4. A railway-tie comprising a sheet-metal body portion, in combination with an open box

carried at the bottom thereof at each end, said box having a depending mouth embedded in the road-bed and preventing displacement of the tie in either direction, substantially as 45 set forth.

5. A railway-tie comprising a sheet-metal body portion, in combination with an open box having a body portion secured to the under side of the tie, and a contracted open mouth 50 embedded in the road-bed and preventing displacement of the tie in either direction, substantially as set forth.

6. In combination with a tie composed of a sheet-metal body portion and depending marginal flanges, a layer of elastic material at 55 each end of the tie, a rail-supporting plate resting on said layer and having terminal flanges embracing said layer on one end, and the layer and the edge of the tie at the opposite end, a spacing-block located centrally on the supporting-plate and having a stem passing through the plate, the cushioning layer and the tie-body, an open box on the under side of the tie at each end thereof, clamps securing the rail to the tie and supporting-plate and having terminal locking-arms passing through the several parts, and bolts for securing the parts together, substantially as set forth.

7. In combination with a tie, an open box supporting the same and embedded in the road-bed, the opposite walls of the box having registering openings for the passage therethrough of a suitable pipe or conduit, substantially as set forth.

In testimony whereof I affix my signature in presence of two witnesses.

HENRY K. J. MANGER.

Witnesses:

EMIL STAREK,
Jos. A. MICHEL.
